UNITED STATES PATENT OFFICE.

ALEXANDER CRUICKSHANK SCOTT, OF LONDON, ENGLAND, ASSIGNOR TO MEXCO LIMITED, OF LONDON, ENGLAND, A BRITISH COMPANY.

EXPLOSIVE.

No Drawing. Application filed July 28, 1926, Serial No. 125,586, and in Great Britain August 12, 1925.

This invention is for improvements in and relating to explosives of the kind in which a salt containing readily available oxygen, e. g. 5 chlorate or perchlorate of potassium or nitrate of ammonia (which salt will herein-after be referred to as the crystals), is first compressed into the form of a cartridge and subsequently the cartridge is impregnated with a nitro-body, such as nitro-benzene, or a 10 hydro-carbon oil, such as kerosene.

Neither nitro-bodies nor hydrocarbon oils have been found completely satisfactory. If a nitro-body, such as nitro-benzene, be employed, this has to be employed in a certain 15 excess in order to overcome the tendency of the nitro-body to become unevenly and incompletely disseminated throughout the mass of crystals, and the presence of an excess of nitro-body has the effect of lowering 20 the energy-density of the charge, that is, the energy per unit of volume. If, on the other hand, a hydrocarbon oil alone be employed, the explosive is difficult to detonate.

The present invention has for one of its objects to meet the difficulty occasioned by the 25 tendency of nitro-bodies to become evenly disseminated throughout the mass of crystals, and a further object is to provide an improved explosive which shall possess a high 30 energy-density and shall, at the same time, be capable of ready detonation.

According to the invention a process for 35 impregnating explosive cartridges of the kind described with a liquid nitro-body is characterized by effecting the impregnation of the cartridge by the aid of a liquid-spreading agent (for example kerosene) which agent has the property of assisting the nitro-body 40 to creep over the surfaces of the crystals and thereby to become evenly disseminated throughout the mass of said crystals, for the purpose of eliminating or reducing the necessity of employing an excess of nitro-body as aforesaid.

45 While the preferred spreading agent is kerosene or like hydrocarbon other liquid hydrocarbons can be employed, for example, xylene, but if xylene is employed it is usually desirable to remove it by evaporation from the explosive after the impregnation has been effected.

The nitro-body employed is preferably one which is miscible with the spreading agent and incorporation can then be effected by impregnating a charge of crystals with a mix-

ture of nitro-body and spreading agent. Alternatively, and especially where the nitro-body and spreading agent are not miscible with one another the liquid nitro-body may first be introduced into a charge of the crystals (for example by immersion of the crystals in the nitro-body) and thereafter the spreading agent is brought in contact with the part of the charge to which the nitro-body has been introduced. It is found according 60 to the above method that the hydrocarbon oil functions as a carrier of the nitro-body to distribute the latter by displacement evenly throughout the mass of crystals in intimate association with itself, practically as 65 though the hydrocarbon and the nitro-body were miscible with one another and had been introduced in admixture.

The invention includes an explosive cartridge of the kind described consisting of a 75 body of crystals having uniformly disseminated throughout their mass after they have been compressed into cartridge form a mixture of liquid nitro-body and a hydrocarbon oil which forms a spreading agent therefor 80 for example kerosene.

The relative proportions of spreading 85 agent and nitro-body may be widely varied. The hydrocarbon oil may be present in proportions (for example from 1% to 4% by weight of the nitro-body) sufficient only to effect spreading of the nitro-body over the 90 crystals. The minimum amount of spreading agent depends upon the particular substances employed but if necessary can readily be determined by experiment in any particular case. On the other hand the hydrocarbon spreading agent may be present in excess of the minimum quantity required to cause spreading, and as spreading agents are 95 themselves effective fuels the only limit to the quantity of them which should be employed depends upon the amount of nitro body which is required to give the desired degree of detonability.

A desensitizing oil, such for example as castor oil, may be incorporated with the charge for the purpose of reducing the sensitiveness of the explosive to friction. Instances of other desensitizing oils are linseed oil, liquid 100 paraffin, wool-fat known as lanoline and heavy oil generally.

Moreover, a cooling agent may be incorporated in the charge if desired with the object of reducing the temperature of the gase- 105

ous products of combustion. Examples of such agents are the nitrates, oxalates and chlorides of sodium, potassium and ammonium, but it is necessary that no ammonium salts be used in charges containing chlorates.

The following examples illustrate the various explosives manufactured in accordance with the invention:—

Example I.

A cartridge prepared as set forth in the specification of United States Patent No. 1,543,798, and containing potassium chlorate as the oxygen-containing salt, is partially immersed in a bath of nitro-benzene, castor oil and kerosene, the nitro-benzene and kerosene being intimately admixed. The nitro-benzene and kerosene are preferably present in the bath in the amounts in which they are intended to be present in the impregnated cartridge, and, according to this example, the amounts of nitro-benzene, castor oil and kerosene are equivalent, in weight, respectively, to about 10%, 1% and 1% of the impregnated contents of the cartridge.

Example II.

A quantity of dinitrotoluene is dissolved in an equal quantity of mononitrotoluene and some castor oil is dissolved therein and a cartridge containing potassium chlorate crystals is partially immersed in the resulting liquid bath. The nitro-bodies are each present in the bath in a quantity equivalent to 4½% of the finally impregnated contents of the cartridge and the castor oil in a proportion equivalent to 1% thereof. When the nitro-bodies have been completely absorbed by the crystals, the cartridge is partially immersed in a bath of kerosene, the kerosene being present in a quantity equivalent to 3% of the finally impregnated contents of the cartridge.

The kerosene, by capillary action, soaks up into the cartridge and carries the previously absorbed nitro-bodies along with it throughout the entire mass of the chlorate crystals and, at the same time, deposits itself in intimate association with the nitro-bodies, uniformly throughout the cartridge.

Example III.

A further example again comprises 20 parts of potassium perchlorate, 35 parts ammonium perchlorate, 30 parts potassium nitrate, 6 parts each of dinitrotoluene and mononitrotoluene and 3 parts of kerosene.

In all of the above examples, the proportions are by weight.

Example IV.

An example of a suitable fuel, for impregnation into a potassium chlorate charge, consists of 40 parts of xylene, 40 parts trinitroxylen, 15 parts of kerosene and 5 parts of

castor oil, the proportions being by weight in each instance.

Example V.

An example of an explosive cartridge embodying the use of cooling agents may be given as follows:—The oxygen-carrying salt comprises a mixture of 33 parts of ammonium nitrate, 20 parts of ammonium perchlorate and 15 parts of sodium nitrate; and a cooling agent consists of 18 parts of sodium chloride, and the fuel consists of 6 parts of dinitrotoluene, 6 parts of mononitrotoluene and 2 parts of kerosene. All the proportions given are by weight and are proportioned to the weight of the completely impregnated charge.

Example VI.

Fuel oil e. g. crude mineral oil or petroleum, preferably having an asphaltic base, may be employed as the hydrocarbon instead of kerosene. According to a further example, the fuel may comprise 69 parts of mononitrobenzene, 17 parts of fuel oil and 14 parts castor oil.

Examples VII, VIII and IX.

When mononitrotoluene is the nitro-body employed, and castor oil is not required, the fuel may comprise 99 parts of the nitro-body and 1 part of kerosene. In the case of the fuel consisting of equal parts of dinitrotoluene and mononitrotoluene, not less than 3 parts of kerosene should be employed to every 97 of the nitro-bodies. The same minimum proportion of kerosene should be employed when the fuel consists of equal proportions of dinitroxylen and mononitrotoluene.

It may be necessary with certain fuel mixtures slightly to raise the temperature in order to provide a sufficiently liquid bath for impregnation.

Various tri-nitro bodies, e. g. trinitroxylen, trinitrotoluene, trinitrobenzene and picric acid may be employed when dissolved in suitable solvents.

I claim:—

1. In a process for impregnating explosive cartridges of the kind described with a liquid nitro-body, effecting the impregnation of the cartridge by the aid of a liquid spreading agent, which agent has the property of assisting the nitro-body to creep over the surfaces of the crystals and thereby to become evenly disseminated throughout the mass of said crystals.

2. In a process for the manufacture of explosives of the kind described, the step of uniformly impregnating a charge of crystals by bringing them in cartridge form into contact with a mixture of a nitro-body and a spreading agent miscible therewith.

3. In a process for the manufacture of ex-

- 5 plosives of the kind described the step of uniformly impregnating a charge of crystals by bringing them in cartridge form into contact with a mixture of a nitro-body and a hydro-
5 carbon spreading agent miscible therewith.
4. In a process for the manufacture of explosives of the kind described the step of uniformly impregnating a charge of crystals by bringing them in cartridge form into contact
10 with a mixture of a nitro-body and kerosene miscible therewith.
5. A process for the manufacture of explosives comprising a crystalline salt containing readily available oxygen and a fuel contain-
15 ing a liquid nitro-body wherein the crystals are first packed to a high density and there-
after the nitro-body is introduced into the cartridges by the aid of a liquid spreading-
20 agent which is capable of assisting the nitro-
body to creep into the fine capillary passages of the cartridge.
6. In a process for the manufacture of explosives of the kind described, the step of im-
25 pregnating a charge of crystals in cartridge form by bringing into contact with them a mixture of a liquefied but normally solid nitro-body and a spreading agent.
7. In a process for the manufacture of explosives of the kind described, the step of im-
30 pregnating a charge of crystals in cartridge form by bringing into contact with them a mixture of a liquefied tri-nitro-body and a spreading agent.
8. In a process for the manufacture of explosives of the kind described, the step of im-
35 pregnating a charge of crystals in cartridge form by bringing into contact with them a mixture of liquefied tri-nitro toluene and a spreading agent.
9. An explosive cartridge of the kind de-
scribed consisting of a body of crystals hav-
ing uniformly disseminated throughout their
mass a mixture of a liquid nitro-body and a
spreading agent which is a hydrocarbon oil.
40
10. An explosive cartridge of the kind de-
scribed wherein the impregnating fuel is uni-
formly disseminated throughout and com-
prises a mixture having as its essential con-
stituents a nitro-derivative of an aromatic
body and a spreading agent.
45
11. An explosive cartridge of the kind de-
scribed wherein the impregnating fuel is uni-
formly disseminated throughout and com-
prises a mixture having as its essential con-
stituents a nitro-derivative of an aromatic
body and kerosene.
50
12. An explosive cartridge of the kind de-
scribed wherein the impregnating fuel com-
prises a mixture having as its essential con-
stituents a nitro-derivative of an aromatic
body and kerosene the amount of kerosene
exceeding 4% of the weight of the nitro-
derivative.
55
13. An explosive cartridge of the kind de-
scribed consisting of a body of crystals hav-
ing uniformly disseminated throughout their
mass a mixture of a liquid nitro-body, a
spreading agent consisting of a hydrocarbon
oil and castor oil.
65
14. An explosive cartridge of the kind de-
scribed consisting of a body of crystals hav-
ing uniformly disseminated throughout their
mass a mixture of a liquid nitro-body, kero-
sene which forms a spreading agent therefor,
and castor oil.
70
- 75 In testimony whereof I have signed my
name to this specification.

ALEXANDER CRUICKSHANK SCOTT.
